UNITED STATES PATENT OFFICE.

LOUIS MAYER, OF ANTIGO, WISCONSIN.

POWER-HAMMER-RAM COUPLING.

1,225,046.

Specification of Letters Patent.

Patented May 8, 1917.

Application filed June 8, 1916. Serial No. 102,385.

To all whom it may concern:

Be it known that I, LOUIS MAYER, a citizen of the United States, and resident of Antigo, in the county of Langlade and State 5 of Wisconsin, have invented certain new and useful Improvements in Power-Hammer-Ram Couplings; and I do hereby declare that the following is a full, clear, and exact description thereof.

10 The present invention relates to power hammers and is directed to the provision of an improved coupling for the ram or hammer head, more particularly of that general type now in common use, and including 15 spring urged yoke arms depending from the wrist pin of the crank wheel and connected with a hollow portion of the ram by T-head links engageable in said hollow portion, whereby a loose coupling is procured to 20 prevent the transmission of jars and shocks from the ram or hammer head to various working parts of the machine.

This type of structure is open to some objection in that considerable expense is involved in the formation of the hollow ram head portion and the T-head links engageable therewith, and this structure is also open to the further objection that should 25 breakage of one of the links occur, considerable difficulty would be encountered in making the particular T-head formation of a link to be substituted therefor.

It is therefore the object of the present invention to provide an arrangement for 30 loosely coupling the ram or hammer head to the yoke arms which may be more economically manufactured and it is further an object to provide a coupling including links of such nature as to permit their ready formation by persons not necessarily supplied 35 with special apparatus or tools.

It is further an object to retain in the present structure, a readily detachable relation of the links and hammer head.

40 With the above and other objects and advantages in view the invention resides more particularly in the novel combination, arrangement and formation of parts more particularly hereinafter described and 45 pointed out in the appended claims.

In the drawings:

Figure 1 is a front elevation of the ram and crank wheel structure of a hammer embodying the present invention.

50 Fig. 2 is a vertical sectional view through an intermediate portion of the structure of

Fig. 1, with other portions of the structure in elevation, this view being indicated more particularly by the line 2-2 of Fig. 1.

Fig. 3 is a transverse sectional view 60 through the coupling on the line 3-3 of Fig. 1.

Referring now more particularly to the accompanying drawings, 5 designates the conventional body structure of a power-65 hammer machine, having at its upper portion the shaft 6 carrying at its forward end a crank wheel 7 on which is eccentrically mounted a pin 8 carrying a pitman link 9 on which is secured a sleeve 10 from which 70 pivotally depends a pair of yoke arms 11 resiliently urged apart by a relatively strong coil spring 12 disposed between their intermediate portions. 13 designates the anvil of the hammer, and reciprocative above this 75 anvil is the hammer head or ram 14 mounted in a vertical dove tail channel 15 carried by the body 5. The lower ends of the yoke arms 11 are bifurcated for pivotal secure-80 ment of the outer ends of links 16 connect- 85 ing said arms with the ram, and all of the structure heretofore described is of a conventional nature. One of the links 16 is adjustably mounted in a sleeve 17 connected with a respective yoke arm whereby an adjustment of the spring tension may be pro- 90 cured.

To form the improved loose coupling between the links 16 and the ram, comprising the present invention, the upper portion of 90 the ram is intermediately cut away to form a recess bounded by the front and rear wall portions 18 and 19 respectively and these wall portions are connected by horizontally 95 spaced integral bar portions 20, the sides 20 of the recesses being thus open to receive the inner ends of the links 16, which are curved in hook shape to engage about the bar portions, and to hold the hooked ends 100 of the links against possible displacement when the links are connected with their respective yoke arms, the bottom portion of 105 the recess, is of substantially inverted V-shape to extend between the inner ends of the links, suitable space, however, being provided between the bar portions and the bottom of the recess whereby a desired looseness of the coupling may be procured.

Thus when connected with the yoke arms, 110 the links can not be detached from the ram, even should a breakage of the spring 12 occur, and the links may be only detached by

swinging them radially upwardly about the bar portions.

The recess and bar portions 20 of the present structure do not interfere with an integral casting of the entire ram structure, and thus a considerable economy of manufacture is procured.

Also the hooked form of the link ends may be more readily made than links including 10 T-shaped heads, and this is most particularly true in providing links as repair parts under such conditions as access to special apparatus for forming the link ends would not be had.

15 I claim:

1. In a ram coupling for power hammers, the combination with a reciprocating ram and pivotally suspended yoke arms of bar portions carried by the ram, and links pivoted to said yoke arms and having their inner ends bent in hook shape to embrace the bar portions of the ram, and other portions of the ram being disposed adjacent said bar portions to hold said links there- 20 against whereby said links may be interlockingly engaged and disengaged with the ram only by rotary movement about the bar portions.

2. In a ram coupling for power hammers, 25 the combination with a reciprocating ram and a pair of pivotally suspended yoke arms

of links pivoted to said yoke arms, the upper end of the ram being cut away to form a recess open at its sides, bar portions extending transversely of the recess and the inner ends of the links being bent in hook shape to engage about said bar portions, and being held against said bar portions by the body of the ram.

3. In a ram coupling for power hammers, 30 the combination with a reciprocating ram and a pair of pivotally suspended yoke arms of links pivoted to said yoke arms, the upper end of the ram being cut away to form a recess open at its sides, bar portions 35 extending transversely of the recess, the inner ends of the links being bent in hook shape to engage about said bar portions, and a projection on the bottom of the recess extending between the inner ends of the links 40 whereby they may be interlockingly engaged and disengaged with the bars only by 45 rotary movement about the bars.

In testimony that I claim the foregoing I have hereunto set my hand at Antigo, in the 50 county of Langlade and State of Wisconsin, 55 in the presence of two witnesses.

LOUIS MAYER.
